UNITED STATES PATENT OFFICE.

WALTER MARSH JACKSON, OF PROVIDENCE, RHODE ISLAND.

GAS-STOVE.

SPECIFICATION forming part of Letters Patent No. 310,946, dated January 20, 1885.

Application filed May 23, 1884. (No model.)

To all whom it may concern:

Be it known that I, WALTER MARSH JACKSON, of Providence, in the county of Providence and State of Rhode Island, have invented certain new and useful Improvements in Apparatus for Utilizing Heat Developed by Combustion; and I do hereby declare the following to be a full, clear, and exact description of the invention, such as will enable others skilled in the art to which it appertains to make and use the same.

My invention relates to an improvement in apparatus for utilizing heat developed by combustion, the object of the same being to provide an apparatus for promoting the combustion of all kinds of gas and obtaining the greatest amount of heat therefrom, a further object being to provide an apparatus adapted to receive a kettle or pot for cooking purposes.

With these ends in view my invention consists in certain features of construction and combinations of parts, as will be hereinafter described, and pointed out in the claims.

In the accompanying drawings, Figure 1 is a view of the apparatus in elevation, partly in section. Fig. 2 is a view of the same, the upper section of the burner being removed, and Fig. 3 is a modification.

A represents a gas-supply pipe, which projects into the enlarged chamber B in the form of a nozzle, a, which, when the gas is turned on, forms an injector. The enlarged chamber B is provided with an air-supply opening, b, having a hand-valve, b', for regulating the supply of air to the gas, the construction and operation of this injector chamber and valve being fully explained in another application, filed May 28, 1884, Serial No. 133,073. A pipe-section, C, connects the injector-chamber B with a safety-chamber, D. The chamber D is provided with a wire-gauze diaphragm suitable to form an effective fire-stop, and at the same time allow a free flow of gas, the general construction and purpose of the chamber D being quite similar to the safety-chamber described in the application above referred to. The safety-chamber D is provided with branch pipes d, which lead to the lower section, e, of an annular burner, E. The burner E consists of an annular chamber formed of two sections—a lower section, e, and an upper section, e'. The lower section,

e, is provided with an outer upwardly-extending flange, F, threaded on its inner face, and with an inner upwardly-extending flange, f, the upper edge of which is provided with a series of radial teeth, f', similar in appearance to saw-teeth. The upper section, e', of the burner is provided with an outer depending-flange, G, threaded, and adapted to register with the upwardly-extending threaded flange F on the lower section. The inner edge of the section e' is flat, and is adapted, when the section is screwed into position, to rest upon and project slightly over the edges of the teeth f', thus forming a series of radial openings extending inwardly from the burner-chamber. The section e' is further provided with three or more upwardly-extending plates, g, cast integral therewith, said plates forming rests for supporting a pot or kettle over the flame of the ignited jets issuing from the saw-tooth perforations f'. The gas-supply pipe A is provided with a stop-cock, x, to regulate the flow of gas, and the apparatus as thus constructed may be secured to the supply-pipe in an upright position for use.

The advantages of this apparatus consist in the regular flow of gas from the saw-tooth notches about the entire inner circuit of the burner, the distance between the jets being of no appreciable value at the edges of the teeth, while a supply of air from below the burner causes the most perfect combustion and the highest degree of heat.

The construction of the burner is also extremely simple and durable, and its combination with my improved air-injector chamber for furnishing any required amount of oxygen to the gas, and the safety-chamber to prevent any possible accident, make the apparatus a most efficient and safe heater.

The modification referred to in Fig. 3 consists simply in providing the lower section, e, of the burner with legs H. The legs are preferably cast integral with the section e, and, to allow the burner to be placed upon a table or any horizontal support, the gas and air supply pipe enters the safety-chamber at the side instead of the bottom.

It is evident that slight changes may be made in the form and construction of the several parts herein described without departing from the spirit and scope of my invention. For ex-

ample, there may be more than two branch-pipes leading from the safety-chamber to the burner, and the upper section of the burner might be secured to the lower section in other ways than by a screw-thread.

10 I make no claim, broadly, in my present application to the injector-chamber, safety-chamber, and annular burner, these forming a part of the subject-matter of separate applications.

15 I am aware that it has been proposed to construct gas-burners of two sections, one section being notched and the other formed to overlap the notched section; but in such cases the notches were either square or semicircular, and sufficiently separated to form separate and independent square or semicircular jets of gas.

20 In my improved burner the saw-tooth notches, in connection with the overlapping section, operate to produce practically a continuous jet or flame of corrugated form, and as the air is allowed to enter the corrugations in the flame it is brought in direct and intimate contact with the flame, and hence is freely and thoroughly commingled therewith.

25 Having fully described my invention, what I claim as new, and desire to secure by Letters Patent, is—

1. A burner consisting of two sections, the wall of one section being provided with a se-

ries of saw-tooth notches, and the wall of the other section constructed to overlap said notches, substantially as set forth.

2. A burner consisting of two screw-threaded sections, the inner wall of one section being notched, and the corresponding wall of the upper section formed to overlap said notches and form gas-jets, substantially as set forth.

3. A burner consisting of two screw-threaded sections, the inner wall of one section being provided with a circuit of saw-tooth notches, and the corresponding wall of the upper section formed to rest upon and project over the edges of the notches and form gas-jets, substantially as set forth.

4. A burner consisting of a lower section with notched wall, and having gas-supply branches cast integral therewith, in combination with an upper section constructed to overlap the notches in the lower sections, substantially as set forth.

45 In testimony whereof I have signed this specification in the presence of two subscribing witnesses.

WALTER MARSH JACKSON.
